Primary Examiner—Robert M. Spear*Assistant Examiner*—Susan Bennett Hattan(74) *Attorney, Agent, or Firm*—Woodcock Washburn LLP**CLAIM**

We claim the ornamental design for a composite closure having an insert with a peripheral curl, as shown and described.

DESCRIPTION

FIG. 1 is a side view of a composite closure having an insert with a peripheral curl according to a preferred embodiment of the design;

FIG. 2 is a top view of the design that is depicted in FIG. 1; FIG. 3 is a bottom view of the design that is depicted in FIGS. 1 and 2;

FIG. 4 is an enlarged cross-sectional view of the design that is depicted in FIGS. 1–3, taken along the line 4/7 in FIG. 2, depicting the closure installed on the neck of a container; FIG. 5 is a top perspective view of the design that is depicted in FIGS. 1–4;

FIG. 6 is a bottom perspective view of the design that is depicted in FIGS. 1–5;

FIG. 7 is an enlarged cross-sectional view of the design that is depicted in FIGS. 1–6, taken along the line 4/7 in FIG. 2; and,

FIG. 8 is an enlarged combination cross-sectional and bottom perspective view of a portion of the closure, shown without the insert for clarity of illustration.

The broken lines shown in the figures are for illustrative purposes only, and form no part of the claimed design.
